REFRIGERATION

Wilhelm Georg Kögel, Stockholm, Sweden, assignor, by mesne assignments, to Servel, Inc., New York, N. Y., a corporation of Delaware

Application May 7, 1936, Serial No. 78,331
In Germany May 31, 1935

1 Claim. (Cl. 62—126)

This invention relates to refrigeration and more particularly to a new and improved cooling element for use in a system which produces refrigeration by the evaporation and diffusion of liquid cooling fluid into inert auxiliary gas.

It is an object of the invention to provide a cooling element having a low temperature chamber for ice making or the like and also having a suitable heat transfer surface for cooling air in a storage compartment of a refrigerator to a temperature suitable for the proper preservation of comestibles.

It is a further object to provide a cooling element which is simple in structure and having substantially independent heat transfer with respect to its air cooling and water freezing parts.

In carrying out the invention, I provide a cooling element comprising an iron pipe coil to which heat is conducted by a sheet metal structure having heat conductivity greater than that of iron. Part of the sheet metal structure is utilized for heat transmission to the coil from freezing chambers surrounded by the coil, and another part of the sheet metal structure which may be in the form of a casing around the coil is utilized for conducting heat to the coil from air in a refrigerator storage compartment. That part of the sheet metal structure utilized for ice freezing purposes may form shelves for receiving ice trays or the like in the freezing compartment and is secured in good thermal conductive relation with the pipe coil. The casing forming the air cooling surface may be arranged in a different thermal conductive relation with the pipe coil, and I provide simple means for predetermineding the relationship between the air cooling casing and the pipe coil.

The invention, together with the objects and advantages thereof, will be more fully understood upon reference to the following description taken in connection with the accompanying drawing forming part of this specification, and of which:

Fig. 1 is a fragmentary sectional view of a refrigerator showing in front elevation a cooling element embodying the invention;

Fig. 2 is a view taken on line 2—2 in Fig. 1;

Fig. 3 is a sectional view taken on line 3—3 in Fig. 2;

Fig. 4 is a detail section taken on line 4—4 in Fig. 2; and

Fig. 5 is a detail section taken on line 5—5 in Fig. 3.

A refrigerator cabinet 10 providing a thermally insulated storage compartment 11 may be pro-

vided with a uniform pressure type absorption refrigeration apparatus of a type generally like that disclosed in United States Patent No. 1,609,334, having a cooling element 12 constructed and arranged in accordance with the present invention. The cooling element 12 comprises an iron pipe coil 13 formed with a plurality of alternate substantially horizontal and vertical U-shaped turns enclosing a freezing area open at the front end. The front end 14 of the coil 12 is connected by a conduit 15 to one part of a gas heat exchanger 16 and the lower end 17 of the coil 13 is connected to another part of the gas heat exchanger 16, the gas heat exchanger 16 being a part of the refrigeration apparatus which is not further illustrated here. Briefly, however, in this type of refrigeration system, an inert gas such as hydrogen is circulated between an evaporator and an absorber, and an absorption liquid such as water is circulated between the absorber and the generator. In the generator, a cooling fluid or refrigerant such as ammonia is vaporized out of solution in the absorption liquid by heat. The vapor is liquefied in a condenser and the refrigerant liquid is conducted to the evaporator in which the liquid evaporates and diffuses into the hydrogen, producing a refrigeration effect. In the absorber, refrigerant vapor is absorbed out of the hydrogen into weakened absorption liquid. The gas heat exchanger 16 is arranged in the circuit between the evaporator 12 and an absorber, not shown. Weak gas flows from the gas heat exchanger 16 through conduit 15 to the upper end 14 of the evaporator coil 13. Liquid refrigerant is also introduced into the upper end 14 of the evaporator coil 13 by means of a conduit 18. In the evaporator coil 13, the liquid refrigerant flows downwardly, evaporating and diffusing into the inert gas. The resulting mixture or rich gas flows from the lower end 17 of the evaporator coil 13 into the gas heat exchanger 16 and thence back to the absorber, not shown.

The pipe coil 13 is constructed and arranged for continuously downward flow of liquid therethrough, but the generally horizontal loops of the pipe coil have leg portions which are substantially opposite one another in the same horizontal plane but have a slight slant in opposite directions. Between the leg portions of the horizontal loops of the pipe coil 13 are shelves or partitions, each formed by an upper plate 19 and a lower plate 20, as may be seen in Figs. 4 and 5. The side edges of the plates 19 and 20 are suitably formed as by stamping to engage there-

between the opposite legs of a horizontal loop of the evaporator coil when the plates 19 and 20 are secured together. The plates 19 and 20 may be secured together and in close thermal contact with the pipe coil by means of rivets 21 and also by tabs 22 and 23. The tabs 22 and 23 are formed on the outer edges of the plates 19 and 20 and are extended through suitable slots 24 in an outer sheet metal casing 25 and overturned 10 on the outside of the casing 25. The plates 19 and 20 and the outer casing 25 may be of copper or tin or any other material of good heat conductivity. The several compartments formed by the shelves comprising plates 19 and 20 may be 15 provided with side walls formed by sheet metal inserts 26 which may also be of copper, tin, or other metal of good heat conductivity.

The outer casing 25 encloses the sides, top, and rear of the cooling element and provides a 20 heat transfer surface for cooling of air in the refrigerator compartment 11. Whereas the shelves formed by plates 19 and 20 are secured in good thermal contact with the evaporator coil 13 the full length of each side of the shelves, 25 the outer casing 25 is brought into thermal conductive relation with the evaporator coil only by means of the connections formed by the previously described tabs 22 and 23. Therefore, the amount of heat transfer from the casing 25 30 to the coil 13 may be varied relative to the heat transfer to the coil 13 from the shelves formed by plates 19 and 20 in accordance with the number of connections formed by tabs 22 and 23. In other words, the greater the number of 35 connections formed by tabs 22 and 23, the greater will be the conduction of heat from the casing

25 to the coil 13. Therefore by providing a certain number of such connections, a given ratio of heat conduction to the coil 13 may be obtained with respect to the freezing compartments and the air in the refrigerator storage compartment. 5

It will be understood that various changes may be made within the scope of the invention. For instance, instead of using two plates 19 and 20, a single plate of suitable thickness may be used and the side edges of the single plate folded 10 around the straight portions of the coil loops and riveted or otherwise clamped thereto in good thermal conductive relation. Also, the outer casing 25 may be provided with fins for increasing the heat transfer surface thereof. 15 Therefore, the invention is not limited except as indicated in the following claim.

What is claimed is:

A cooling element comprising an iron pipe coil 20 adapted for circulation of inert gas and continuously downward flow of liquid therethrough, said coil comprising a plurality of substantially horizontal superposed U-shaped turns, shelves each formed by two sheets of metal having greater conductivity than iron, said sheets being secured together and having their side edges formed to engage opposite legs of said coil turns in good thermal contact, said sheets of metal having tabs extending outwardly from their side edges, and a sheet metal casing around said coil 25 forming a freezing chamber open at the open end of said turns, said casing being provided with slots through which said tabs extend for securing said casing. 30
